UNITED STATES PATENT OFFICE.

KYLE E. STANT, OF CONNERSVILLE, INDIANA, ASSIGNOR TO THE STANT MACHINE COMPANY, OF CONNERSVILLE, INDIANA, A CORPORATION OF INDIANA.

RADIATOR CAP.

Application filed June 23, 1927. Serial No. 200,860.

My invention relates to a radiator cap for automobiles.

The object of my invention is to provide a radiator cap consisting of an annular body portion, a hinged member hinged thereto and a cap cover pivotally mounted on the hinged member eccentrically of the center of the cap cover so that the cap cover can move with the hinge for opening and closing the body portion, and can also move laterally thereof in order to effect a locking between the cap cover and body portion through a bayonet joint or other interlocking means. Thus, it is my object to accomplish the use of a hinged cap cover, which will have lateral movement of the body within a limited degree to permit of the locking and unlocking of the cap cover.

It is a further object of my invention to provide in this combination the additional cooperating feature of a yielding diaphragm closure carried by the cap engaging a sealing member carried by the body of the radiator cap and so arranged as to permit of the adjustment of one to the other, and a yielding closure to be effected irrespective of the exact position and lateral location of one member with respect to the other as a result of the lateral movement provided by the eccentric pivoting of the cap cover on the hinge. Thus, it is my object to provide a yielding sealing means adapted to this lateral movement to prevent rattling at the hinge. It is a further object of my invention to provide means on the hinge of not only eccentrically pivotally supporting the cap cover but of limiting the movement laterally thereon and also with respect to the body and the radiator cap.

Referring to the drawings:

Figure 1 is a central vertical section through the closure showing it in closed position;

Figure 2 is the same as Figure 1 showing it in open position;

Figure 3 is a section taken on the line 3-3 of Figure 1;

Figure 4 is a section taken on the line 4-4 of Figure 2.

In the drawings there is shown a portion 60 of a radiator having a neck 10 to which the radiator cap or closure is adapted to be secured. Said closure comprises the body portion 11 which is screw-threaded upon the neck of the radiator in the usual manner and locked in position thereon by the headless screw 12. Said body portion is provided with an annular opening therethrough in the usual manner, which is surrounded by a gasket ring 13 to provide a seat for the closure 60 cap. On the forward side of the body, there is an upwardly-extending keeper 14 and on the other side thereof there is a recessed portion for receiving the hinge mounting of the cap cover.

The hinged cap or cover portion of the closure comprises the usual disk cover 15 having detachably mounted on the top thereof an ornamental figure or device 16. The cover is provided with a central opening 17 therethrough and an annular boss 18 surrounding said opening, to which is secured a resilient retaining ring 19 suitably spaced from the shoulder 20 and formed on the cover so as to receive therebetween a 75 substantially oval supporting member 21. Said oval member is constructed at one end in the form of an eye or loop which surrounds the boss 18 and is so fashioned as to be movable laterally with respect thereto, as 80 best illustrated by the positions of the cover 15 with respect to the supporting member 21, as shown in Figures 3 and 4.

The member 21 is held in place and pivotally connected with the cover through the 85 pivot pin or rivet 22 and it is further provided with a projecting portion 23 which is pivotally mounted on the body portion of the closure by the hinge pin 24. By means of this arrangement, it will be apparent 90 that the cover 15 will have lateral movement with respect to the support 21 about the pivot pin 22, while the cover and support together will swing to closed or open position about the hinge pin 24.

Mounted on the under side of the cover there is a spring seating disk 25 which is secured in position on the cover by a rivet-

ing over the end of the boss 18, thereby making this joint steam tight. Said spring seating disk is so positioned that, when the cover is in closed position, as illustrated in Figure 1, its edges bear resiliently against the gasket 13, thus sealing the opening and preventing escape of the contents of the radiator or other container. Said disk is held under spring tension in its sealing position, and the cover in its closing position by the engagement and interlocking of the latch projection 27, formed on the under surface of the cover adjacent the forward edge thereof, with the keeper 14.

From the foregoing, it will be observed that the cover may be readily closed by swinging the same to closed position about the hinge pin 24, and causing the cover to be in the position relative to the supporting member 21 about the pivot pin 22, as shown in Figure 4, so that the latch projection 27 will fall to one side of the keeper 14. Thereupon, by a simple lateral movement of the cover with respect to the supporting member 21 about said pivot pin, the latch projection 27 may be forced laterally into locking engagement with the keeper 14 against the spring pressure of the resilient disk 25. Thus the disk 25 will act to maintain the cap in such locked position under spring tension and at the same time effect a resilient seal in contact with the gasket 13. Thereupon the cover will have a position with respect to the supporting member as shown in Figure 3. It follows from the above that to open the closure, it is only necessary to again move the cap laterally, exerting a force thereon sufficient to overcome the spring tension of the disk 25, thus moving the latch out of engagement with the keeper, whereupon the cover may be readily swung into open position as shown in Figure 2.

While the invention has been described in detail with respect to a radiator cap, it is apparent that it is applicable to various types of closures for containers, and the spring securing disk may be either formed of spring metal as illustrated herein, or of a rigid character having a spring support or mounting whereby it will yield with respect to the cover and supporting member.

It will be understood that I desire to comprehend within my invention such modifications as may be necessary to adapt it to varying conditions and uses.

Having thus fully described my invention, what I claim as new and desire to secure by Letters Patent, is:

1. In a radiator cap, a stationary body portion, a hinge member hinged thereto, and a cap cover eccentrically pivoted on said hinge.

2. In a radiator cap, a stationary body portion, a hinge member hinged thereto, a cap cover eccentrically pivoted on said

hinge member, and a bayonet lock between said stationary body portion and said cap cover.

3. In a radiator cap, a body portion, a hinge pivoted to the margin thereof and a cap cover pivotally mounted on said hinge at a point off of the center of the cap cover, and means on said hinge and on said cap cover for limiting the relative lateral movement of one to the other. 75

4. In a radiator cap, a body, a hinge member hinged to the margin thereof having an arm extending inwardly towards the center of the body, a cap cover pivotally mounted on said hinge arm at a point off of the center of the body and cap cover, whereby the cap cover may move about said pivotal connection on the hinged arm and relative to the stationary body, and means to lock and unlock said cap cover and body through 80 said lateral movement. 85

5. In a radiator cap, a stationary annular body, a hinge member hinged to the margin thereof having an inwardly extending arm extending above said body and terminating in an eye, a cap cover adapted to interlock with said body by a lateral movement relative to said body, means to pivot said cap cover on said hinged member eccentrically 90 of the center of the cap cover, and an annular depending member on the interior of said cap cover adapted to engage the margin of the eye portion of said hinge member. 95

6. In a radiator cap, a body portion, a hinge member hinged thereto, a cap cover eccentrically pivoted on said hinge member, and resilient means for maintaining said hinge member and cap cover in yielding engagement with one another to prevent rattling without preventing the lateral 100 movement of one with respect to the other. 105

7. In a radiator cap, a body portion, a hinge member hinged thereto having an eye on the end thereof, a cap cover eccentrically pivoted on said hinge member, a member depending from said cap cover, a resilient means mounted on said depending member engaging with said eye portion of the hinge member to yieldingly retain said eye portion against the under side of said cap member. 110 115

8. In a radiator cap, a body portion, a hinge member hinged thereto having an eye on the end thereof, a cap cover eccentrically pivoted thereon, a member depending from said cap cover, a resilient means mounted on said depending member having the ends thereof engaging with said eye portion of the hinge member to yieldingly retain said eye portion against the under side of the cap cover, said depending member being arranged within said eye portion to limit the lateral movement of the hinge member and the cap cover with respect to one another. 120 125

9. In a radiator cap, a stationary body 130

- portion, a hinge member hinged thereto, a cap cover eccentrically pivoted on said hinge, a resilient diaphragm carried by said cap cover adapted to engage with the body portion, whereby a sealing engagement is effected between the cap cover and body portion, while the lateral movement of one or the other is not prevented.
10. In a radiator cap, a stationary body portion, a hinge member hinged thereto, a cap cover eccentrically pivoted on said hinge, and a bayonet lock between said stationary cover and said portion covered, a resilient diaphragm carried by said cap cover adapted to engage with the body portion whereby a sealing engagement is effected between the cap cover and body portion while the lateral movement of one on the other is not prevented.
15. In a radiator cap, a stationary body portion, a hinge member hinged thereto, a cap cover eccentrically pivoted on said hinge, and a locking means for locking said cap cover and stationary body one to the other, and means for preventing the rattling of the hinge member when the parts are locked one to the other, and a sealing means adapted to seal said cap cover and body one to the other.
20. 11. In a radiator cap, a stationary body portion, a hinge member hinged thereto, a cap cover eccentrically pivoted on said hinge, a locking means for locking said cap cover and stationary body one to the other, and means for preventing the rattling of the hinge member when the parts are locked one to the other.
25. 12. In a radiator cap, a body portion, a hinge pivoted to the margin thereof and a cap cover pivotally mounted on said hinge at a point off of the center of the cap cover, and means on said hinge and on said cap cover for limiting the relative lateral movement of one to the other, and a resilient diaphragm carried by said cap cover adapted to engage with the body portion whereby a sealing engagement is effected between the cap cover and body portion while lateral movement of one on the other is not prevented.
30. 13. In a radiator cap, a body, a hinge member hinged to the margin thereof having an arm extending inwardly towards the center of the body, a cap cover pivotally mounted on said hinged arm at a point off of the center of the body and cap cover, whereby the cap cover may move about said pivotal connection on the hinged arm and relative to the stationary body, and means to lock and unlock said cap cover and body through said lateral movement, and a resilient diaphragm carried by said cap cover adapted to engage with the body portion whereby a sealing engagement is effected between the cap cover and body portion while lateral movement of one or the other is not prevented.
35. 14. In a radiator cap, a stationary annular body, a hinge member hinged to the margin thereof having an inwardly extending arm extending above said body and terminating in an eye, a cap cover adapted to interlock with said body by a lateral movement relative to said body, means to pivot said cap cover on said hinged arm eccentrically of the center of the cap cover, and an annular depending member on the interior of said cap member adapted to engage the margin of the eye portion of said hinge member, and a resilient diaphragm carried by said cap cover adapted to engage with the body portion whereby a sealing engagement is effected between the cap cover and body portion while lateral movement of one or the other is not prevented.
40. 15. In a radiator cap, a stationary body portion, a hinge member hinged thereto, a cap cover eccentrically pivoted on said hinge, a locking means for locking said cap cover and stationary body one to the other, and means for preventing the rattling of the hinge member when the parts are locked one to the other, and a sealing means adapted to seal said cap cover and body one to the other.
45. 16. In a radiator cap, a body portion, a hinge member hinged thereto, a cap cover eccentrically pivoted on said hinge member, and resilient means for maintaining said hinge member and cap cover in yielding engagement with one another to prevent rattling without preventing the lateral movement of one with respect to the other, and a resilient diaphragm carried by said cap cover adapted to engage with the body portion whereby a sealing engagement is effected between the cap cover and body portion while lateral movement of one or the other is not prevented.
50. 17. In a radiator cap, a stationary body portion, a hinge member hinged thereto, a cap cover eccentrically pivoted on said hinge, a diaphragm carried by said cap cover, and a sealing member carried by the body portion adapted to cooperate with said diaphragm for effecting a complete sealing of the parts with respect of one to the other.
55. 18. In a radiator cap, a stationary body portion, a hinge member hinged thereto, a cap cover eccentrically pivoted on said hinge, a diaphragm carried by said cap cover, a bayonet lock between said stationary body portion and said cap cover, and a sealing member carried by the body portion adapted to cooperate with said diaphragm for effecting a complete sealing of the parts with respect of one to the other.
60. 19. In a radiator cap, a stationary body portion, a hinge member hinged thereto, a cap cover eccentrically pivoted on said hinge, and a bayonet lock between said stationary cover and said portion covered, and a yielding diaphragm adapted to seal the engaging portions of the stationary and cover portions, and a sealing member carried by the body portion adapted to cooperate with said diaphragm for effecting a complete sealing of the parts with respect of one to the other.
65. 20. In a radiator cap, a body portion,

hinge pivoted to the margin thereof, and a cap cover pivotally mounted on said hinge at a point off of the center of the cap cover, a diaphragm carried by said cap cover, and means on said hinge and on said cap cover for limiting the relative lateral movement of one to the other, and a sealing member carried by the body portion adapted to co-operate with said diaphragm for effecting a complete sealing of the parts with respect 10 of one to the other.

In testimony whereof I affix my signature.

K. E. STANT.
